MEDAL

Gertrude Lanz, Port Chester, N. Y.

Application August 21, 1953, Serial No. 26,547

Term of patent 14 years

(Cl. D29—19)

To all whom it may concern:

Be it known that I, Gertrude Lanz, a citizen of the United States and a resident of Port Chester, county of Westchester, State of New York, have invented a new, original, and ornamental Design for a Medal, of which the following is a specification, reference being had to the accompanying drawing, forming a part hereof.

Fig. 1 is a front elevational view of a medal showing my new design;

Fig. 2 is an edge view thereof; and

Fig. 3 is a perspective view thereof drawn on a slightly larger scale.

The back of the medal is plain.

I claim:

The ornamental design for a medal, as shown and described.
